POISING TOOL FOR WATCHMAKERS

Jes I. Hansen, Denver, Colo.

Application April 5, 1940, Serial No. 327,981

1 Claim. (Cl. 81—6)

This invention relates to a tool for watchmakers and more particularly to a tool for poising and aligning balance wheels. The principal object is to provide a simple, neat, and efficient device for use on a watchmaker's bench in which a balance wheel can be quickly and easily placed with its staff pivots supported in jeweled bearings so that it can be accurately poised.

Other objects of the invention are to provide a device of this character which can be quickly and accurately adjusted to receive balance staffs of various lengths; which will be provided with a magnifying lens which can be easily adjusted to the proper position for observing the balance wheel and staff pivots; and to provide means whereby the alignment of the balance wheel and staff can be easily checked.

Other objects and advantages reside in the detail construction of the invention, which is designed for simplicity, economy, and efficiency. These will become more apparent from the following description.

In the following detailed description of the invention reference is had to the accompanying drawing which forms a part thereof. Like numerals refer to like parts in all views of the drawing and throughout the description.

In the drawing:

Fig. 1 is a perspective view of the improved watchmaker's tool as it would appear in use.

Fig. 2 is a top plan view with a magnifying glass in place thereon.

Fig. 3 is a detailed enlarged view illustrating the extremities of the jeweled bearing bars with a balance wheel in place therein, and with a pivot straightening screw in place therein.

Fig. 4 is a front view of the improved tool.

Figs. 5 and 6 are detail, perspective views of the jeweled bearing bars.

Fig. 7 is a detail view of a type of vibrating tool which may be employed with this invention.

Fig. 8 is a side sectional view, taken on the line 8—8, Fig. 2.

Fig. 9 is an enlarged sectional view illustrating the position and construction of a pivot straightening screw which may be employed with the invention.

For the purpose of illustration, a typical watch balance wheel is illustrated at 37, with its staff at 38, and its staff pivots at 36.

The improved watchmaker's tool consists of a frame plate 10, terminating at its rearward extremity in two bench engaging legs 11 and at its forward extremity in two clamping arms 12. A finger hole 13 is formed through the mid-

portion of the frame 10 in which the operator's finger is pressed to hold the tool stationary on the bench while in use.

The forward extremity of the frame plate 10 is supported on two knurled legs 14 which are held in place by means of threaded extremities 15. The arms 12 are split, as shown at 16, on a plane parallel with and intermediate of the surfaces of the plate 10. The threaded extremities of the legs are threaded into the plate 10 in that portion above the split 16 so that when they are screwed tightly into place, they will act to contact the splits 16. The legs serve the double purpose of supporting the plate 10 and clamping the splits.

The arms 12 are drilled in alignment with each other through the splits 16 to receive two jeweled bearing bars 17 and 18. The bearing bars 17 and 18 are formed with knurled heads 19 at their outer extremities and, when the legs 14 are loosened, they may be slid freely through the arms 12. The inner extremities of both arms are provided with notches 20 extending slightly more than one-half the way through the bars. These notches are placed sufficiently close to the ends of the bar to leave a relatively thin jewel plate 21 thereon.

In each jewel plate a standard balance wheel pivot jewel is mounted. The bar 17 carries a full complete jewel 22. The bar 18 carries one-half of a complete jewel 23. The half jewel is formed by finishing the bar 18 exactly similar to the bar 17 and then cutting the jewel plate 21 and the jewel diametrically in half.

Some of the tools have been manufactured in which both jewels are cut in half similar to the one shown in Fig. 5. This facilitates the placement of the balance staff pivots thereon but such a construction does not hold the pivots as securely against displacement as a construction in which one of the jewels remains complete.

In use the bearing bars 17 and 18 are adjusted in the plate 10 to the length of the balance staff 38 of the wheel 37 to be poised. The bars are then clamped in their adjusted positions by tightening the legs 14. The tool is then placed on the watchmaker's bench and held by placing the forefinger of the one hand in the opening 13 to hold the tool against the bench, while the balance staff pivots 36 are inserted in the jewels with the other hand.

The pivot at one extremity of the balance staff is first inserted in the complete jewel 22 and the other pivot is dropped into the half jewel 23. The device is then vibrated to cause the heavy side, if any, of the balance wheel to gravitate to the

bottom. This vibration may be accomplished by means of a knurled vibrating tool 24, as shown in Fig. 7. The knurled portion of this tool is drawn across the projecting portions of the bars 17 and 18 to vibrate the wheel.

To facilitate observation of the wheel and its pivots, a magnifying lens 25 may be provided, mounted in a suitable frame 26 from which a supporting arm 27 extends to a friction clamp member 28. The friction clamp is slidably mounted on a post 29. The post passes through an opening in the plate 10 and may be locked in any desired position therein by means of a knurled set screw 30.

The lens 25 may be provided with an index line 31 which by swinging the lens may be brought into alignment with the plane of the balance wheel. By rotating the wheel and comparing it with this line it can be quickly determined whether the wheel is true with its shaft pivots.

A second index line 32 crossing the first line at right angles can be brought into alignment with the axes of the two bearing jewels to determine, by the wobble of the staff, the straightness of the staff pivots.

A pivot straightening screw 33 may be threaded through the bottom of the slot 20 in the bearing bar 17. The extremity of this screw is cupped as indicated at 34 to provide a raised, rounded, peripheral edge 35 one side of which contacts the staff pivot 36 of the balance wheel. A knurled

head 37 is formed on the screw 33 by means of which it may be rotated to bring pressure against the staff pivot 36 for straightening the latter. It will be noted that the raised edge 35 is rounded so that it will contact the pivot at a single point for accurate straightening effect.

While a specific form of the improvement has been described and illustrated herein, it is desired to be understood that the same may be varied, within the scope of the appended claim, without departing from the spirit of the invention.

Having thus described the invention, what is claimed and desired secured by Letters Patent is:

A watchmaker's poising tool comprising: a frame plate; arms projecting from said frame plate; a bearing bar in each arm, said bars being directed toward, and in alignment, with each other; means for supporting a balance staff between the adjacent extremities of the bars, the adjacent extremities of the bearing bars being transversely notched to a depth exceeding one-half of their diameters; jewel retaining portions on said bars between the extremities and said notches; a jewel mounted in the retaining portion of each bar for receiving the pivot of a balance staff; and a pivot straightening screw threaded through the bottom of the transverse notch in one of said bearing bars to contact the staff pivot positioned in the jewel of said bar when desired.
